CHARLES R. FOWLER, OF PHILADELPHIA, PENNSYLVANIA.

RADIATOR-SUPPORT.

1,924,916.

Specification of Letters Patent.

Patented May 3, 1917.

Application filed October 28, 1916. Serial No. 127,357.

To all whom it may concern:

Be it known that I, CHARLES R. FOWLER, a citizen of the United States, residing at Philadelphia, county of Philadelphia, and State of Pennsylvania, have invented a certain new and useful Improved Radiator-Support, of which the following is a specification.

The present invention relates to radiator supports and has for an object to provide a hanger or support for use, more particularly, with radiators of the wall type and which in addition to being adjustable to meet varying conditions is adapted to accommodate itself to movements of the radiator due to expansion or contraction and places no restriction upon such movement.

A further object of the invention is to provide a radiator support, which is applicable for use as a direct wall attachment or as a part of a floor bracket and also capable of lateral swinging movement about a substantially vertical axis whereby any movement of the radiator caused by changes in temperature is transmitted to said support so that the latter moves freely with the radiator in the direction of movement.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

40 Referring to the drawings:

Figure 1 represents a front elevation of a radiator support embodying my invention.

Fig. 2 represents a section of the same on line 2—2 of Fig. 1.

Fig. 3 represents a vertical section on line 3—3 of Fig. 1.

Fig. 4 represents a front elevation of a modification of the invention.

50 Fig. 5 represents a rear elevation of the same.

Fig. 6 represents a section on line 6—6 of Fig. 4.

Fig. 7 designates a plate or base adapted to be secured to a wall or the like to serve as a retaining bearing for the part or parts

which are adapted to support a radiator. The base 1 preferably forms a tubular body 2 having a slot 3 open at one end to permit the insertion of the radiator support proper 60 and closed at its lower end for the accommodation of a suitable adjustment. The body 2 provides a substantially cylindrical bearing and guide for the cylindrical stem or pivot 4 which carries a laterally extending hook 5 projecting through the slot 3 into position to receive and support a radiator section, and to that end the upper face 6 of said hook 5 is suitably shaped in order to conform to the contour of the lower 70 face of the said radiator section. A notch or seat 7 is preferably formed in said hook 5 for the purpose of engaging a rib, flange or like projection on the bottom of the radiator, thus substantially interlocking the 75 parts to prevent lateral displacement.

8 designates a threaded opening in the bottom wall of the body 2 and in alignment with the stem 4 so that the latter may be adjusted at will by the adjusting stud 9 which 80 operates through the opening 8. In connection with the cylindrical stem 4 and its bearing, it will be noted that the former is fitted to slide freely in the bearing, though of course with little lost motion while the 85 thickness of the protruding hook 5 is substantially less than the width of the slot 3, so that a side to side movement of the hook may take place, the arc of which is of sufficient length to take care of the expansive 90 or contractive movement of a radiator section. The base 1, as here shown, is adapted to be fixed to the wall upon which the radiator is to be supported and it may either be held fast by bolts engaging the recesses 10 95 or by an expansion bolt or other fastening means passing through the opening 11. When the base 1 is accurately fixed in position at a place adjacent the bottom of the 100 radiator section, the radiator is then positioned upon the supporting hook and the latter raised or lowered as required by the operation of the adjusting stud 9. Of course, it will be understood that there are as many supports or hangers used as are 105 necessary for the required work, all of which operate to the common end of supporting a radiator from the wall and in such a manner that free movement is permitted under expansion or contraction.

In Fig. 4 a modified form of the device is shown for use with radiators which are

to be supported directly from the floor, and to that end, I have provided a bracket 12 of suitable height to support the radiator at the bottom and also clamp or hold the 5 same at a point adjacent the top of the radiator. This bracket 12 is preferably formed with a laterally disposed foot piece 13 which is adapted to rest upon the floor and be fixed thereto in any well known 10 manner, as will be understood, while the vertical portion of the bracket is fixed to the wall by a suitable bolt or the like passing through the opening 14. That portion of the bracket which is adjacent the lower end 15 or bottom of the radiator is in the present instance, for purposes of adjustment, provided with a plurality of openings 15 positioned one above the other, any one of which may receive a lug 16 secured to or formed 20 integral with the plate 17. This plate 17 corresponds substantially to the plate 1, heretofore described, since it forms a bearing for the movable radiator supporting element 5 and as this latter does not differ in 25 construction from that already described the same reference numerals will be applied thereto. In this modification it will be noted that the plate 17 is removably secured to the bracket 12 and has also provision for 30 vertical adjustment of the said plate upon the bracket 12. This adjustment in the present instance consists of a bolt 18 passing through the opening 11 of the plate and also through a vertically disposed slot 19 35 in the bracket 12 and having its nut guided between suitable ribs 20 of the bracket whereby free sliding movement is permitted but turning movement of the nut is prevented. The upper end of the plate 17 may 40 therefore be locked securely by actuating the bolt from the front of the bracket after the height has been determined by the opening 15 in which the lug 16 is located. This modification is adapted more particularly 45 for use with wall radiators of the type supported from the floor at the bottom and from the wall at the top and in adjusting to the required position the plate 17 is first 50 located upon the bracket 12 in such a position as to bring the hook or hanger 5 as near as can conveniently be done to the line of the bottom of the radiator. This adjustment is accomplished by locating the lug 16 in the opening 15 nearest to the position 55 desired; it is then locked by drawing the bolt 18 tight and then the more accurate adjustment is made through the medium of the stud 9 which is moved to bring the hook or hanger into contact with the bottom of 60 the radiator so that the latter is supported in the required manner.

21 designates an undercut slot formed in the top portion of the bracket 12 for the purpose of adjustably holding the T-head bolt 22 which carries a suitable adjusting

nut 23 for engaging the radiator and holding the top in position as will be understood.

From the foregoing, it will be apparent that I have provided a complete unitary structure embodying as an essential feature a movable hanger or support which co-operates with the expanding or contracting movement of a radiator in such a manner as to relieve any fixed parts from strain during such movement. In this connection, it should be noted that the hanger or hook support operates substantially in a horizontal plane of movement having a substantially vertical axis as the pivot about which it moves. The guide slot 3 in the bearing plate is preferably of sufficient width as to freely receive the support or hanger 5 and permit the required range of movement in either direction. In addition to lateral movement the support 5 is also capable of adjustment vertically and may be readily and easily adjusted while carrying the weight of the radiator to meet the required conditions of support. In the modified form 90 employing a foot bracket, it will be evident that an extremely wide range of vertical adjustment is possible owing to the fact that the bracket is provided with a plurality of superposed openings with any one of which 95 the plate supporting lug may be engaged. Thus several inches rough adjustment exists between the bracket and plate while a more delicate and accurate adjustment is also possible between the support 5 and the 100 plate 17.

Attention is directed to the fact that while I have shown a notch engaging the section rib as one means to prevent lateral displacement of the radiator, I do not wish to be restricted to this exact construction, as obviously, this may be varied in many particulars to accomplish the same result.

It will now be apparent that I have devised a novel and useful construction which embodies the features of advantage enumerated as desirable in the statement of the invention and the above description and while I have in the present instance shown and described the preferred embodiment thereof 110 which has been found in practice to give satisfactory and reliable results, it is to be understood that the same is susceptible of modification in various particulars without departing from the spirit or scope of the 115 invention or sacrificing any of its advantages.

What I claim is:

1. In a device of the character stated, the combination of a base adapted to be secured to a fixed part, a substantially cylindrical slotted bearing formed in said base, a pivot member mounted in said bearing for free turning movement and a radiator support connected to said pivot member and extend- 125
- 130

ing laterally from said base whereby a radiator seating upon said support is held in operative position and is free to expand and contract.

5. 2. In a device of the character stated, the combination of a base adapted to be secured to a fixed part, a support pivotally carried by said base and adapted to support a radiator and move laterally with said radiator
10 under expansive and contractive movement and means between said support and radiator to prevent displacement of said radiator.

3. In a device of the character stated, the combination of a base adapted to be secured to a fixed part, a support pivotally carried by said base and adapted to support a radiator and move laterally with said radiator under expansive and contractive movement,
20 means between said support and radiator to prevent displacement of said radiator and means to adjust said support longitudinally of said base.

4. In a device of the character stated, the combination of a bracket adapted to be secured to a fixed part, a base mounted upon said bracket, means between said bracket and base to adjust the relative position of one of said parts with respect to the other
30 and a laterally disposed support pivotally mounted on said base for lateral movement in a horizontal plane, said support being adapted to hold a radiator and move with said radiator under expansive or contractive movement.

5. In a device of the character stated, the combination of a bracket adapted to be secured to a wall and having a foot piece adapted to be secured to the floor, said bracket also being provided with a plurality of superposed openings, a base provided with means to engage any one of said openings for adjustment purposes, means to lock said base in adjusted position and a laterally disposed support pivotally mounted on said base for lateral movement in a horizontal plane, said support being adapted to hold a radiator and move with said radiator under expansive or contractive movement.

6. In a device of the character stated, the combination of a bracket adapted to be secured to a wall and having a foot piece adapted to be secured to the floor, said bracket also being provided with a plurality of superposed openings, a base provided with means to engage any one of said openings for adjustment purposes, means to lock said base in adjusted position, a laterally disposed support pivotally mounted on said base for lateral movement in a horizontal plane, said support being adapted to hold a radiator and move with said radiator under expansive or contractive movement and means to adjust said support with respect to said base.

7. In a device of the character stated, the combination of a bracket adapted to be secured to a fixed part, a base or body mounted upon said bracket, means between said bracket and body to adjust the relative position of one of said parts with respect to the other, a laterally disposed support mounted on said base for lateral movement in either direction, said support being adapted to hold a radiator and move with said radiator under expansive or contractive movement and means adjustably secured to the upper portion of said bracket for engaging said radiator.

8. In a device of the character stated, the combination of a bracket adapted to be secured to a fixed part and provided with an undercut groove at one end and a plurality of superposed openings at the opposite end, a base provided with means to engage any one of said openings for adjustment purposes, means to lock said base in adjusted position, a laterally disposed support pivotally mounted on said base for lateral movement in a horizontal plane, said support being adapted to hold a radiator and move with said radiator under expansive or contractive movement, means to adjust said support vertically and clamping means cooperating with said undercut groove to hold said radiator in operative position.

CHARLES R. FOWLER.
